ROCKET GAS GENERATOR FOR TURBOFAN
ENGINE

Abraham M. Landerman, Hartford, Conn., assignor to
United Aircraft Corporation, East Hartford, Conn., a
corporation of Delaware

Filed Apr. 5, 1957, Ser. No. 650,909
3 Claims. (Cl. 60—35.6)

This invention relates to turbine type power plants and, more specifically, to a combination rocket and air turbojet power plant.

It is an object of this invention to provide a power plant of the type described and utilizing a high energy fuel stored in a liquid state and burned in a gaseous state.

A further object of this invention is to provide an air liquefier wherein the low temperature fuel is passed in heat exchange relation with air from a suitable source. The broad concept of this type of device is disclosed and claimed in a copending patent application Serial No. 650,913 filed by Wesley A. Kuhrt as of even date. The present invention in addition to other features further includes a regenerative heat exchanger in which liquid and gaseous air are passed in heat exchange relation.

It is a further object of this invention to provide a rocket chamber which discharges gases through a turbine which in turn discharges into a main combustion chamber. Means is also provided for two variable area exhaust nozzles in series.

These and other objects of this invention will become readily apparent from the following detailed description of the drawing, in which:

FIG. 1 is a partial cross section and partial schematic illustration of the power plant cycle of this invention, and

FIG. 2 is an enlarged detailed cross section of a typical variable stator vane turbine construction.

Referring to the drawing, a power plant is generally indicated at 10 and includes an inner body 12 which has a conical leading edge spike 14 which cooperates with an outer casing 16 to define an annular passage 18. The annular passage 18 has an inlet 20 at the upstream end thereof which leads to a compressor or fan 22. The inner wall 24 formed by the inner body 12 includes a passage 26 for bleeding off boundary layer air and emitting this air through suitable hollow streamlined struts 28 through the exits 30 leading outboard of the power plant. The inner body 12 carries the compressor 22 and extends aft thereof forming a chamber 34 which houses a plurality of primary rocket type combustion chambers 36 which exhaust gases into the turbine 38 which drives the compressor 22 via a gear box 40. The gases exhausted from the turbine 38 pass through a nozzle 42 having movable elements 44 for varying the area of the nozzle 42. The area may be varied by any suitable mechanism, as, for example, that shown in Patent No. 2,714,285. Gases emitted from the exhaust nozzle 42 pass to a main combustion chamber 48 where the gases mix with the air coming from the compressor 22 and are burned adjacent the flameholders 50. The flameholders 50 are combined with fuel spray bars 51 which discharge fuel in the gutters formed by the V-type flameholders. Downstream of the main combustion chamber is a convergent-divergent nozzle 52 which may include movable members 54 for varying the area of the nozzle 52. The members 54 may be moved for varying the area of the nozzle by any suitable means as, for example, shown in Patent No. 2,714,285 mentioned above.

As seen in FIG. 2, the turbine 38 has nozzles upstream thereof which nozzles are formed by stator vanes 55. The vanes 55 are pivoted at 56 and carry arms 57 which

2

can be simultaneously moved by a ring 58 to vary the angle of the blades. This motion will vary the geometry of both the throat and exit area of the nozzles formed by the vanes 55. The throat of the nozzles formed by the vanes 55 is varied so that the combustion chamber pressure is held constant as the flow through the main part of the power plant changes during flight.

With variable stator vanes 55, the nozzle 42 may or may not be of variable area.

Referring again to FIG. 1, the fuel for the power plant is preferably a high energy fuel such as hydrogen which is stored in a liquefied state in a suitable container 60. Liquid hydrogen from the tank 60 is pumped by means of a high pressure pump 62 through small diameter tubes 15 72 of a main heat exchanger 64 where the hydrogen is heated and passed through a conduit 66. Some of the fuel passes directly from pump 62 to line 66 without going through the heat exchanger tubes 72. The amount which bypasses the heat exchanger may be regulated 20 by the valve 63.

From line 66 the fuel flows through coils 65 which surround the combustion chamber or afterburner 48 for cooling the afterburner. After leaving the coils 65 the fuel is divided by a valve 67 so that some of the fuel flows directly to the fuel spray bar 51. The remaining 25 then flows to the rocket type combustion chambers 36. The other heat exchange medium of the heat exchanger 64 is precooled gaseous air which is conducted to the conduit 70 around the tubes 72 to a liquid air pump 74. The precooled air from the conduit 70 is liquefied in the 30 heat exchanger 64 from whence it is pumped by the liquid air pump 74.

Liquid air flows through the line 76 to a regenerative or precooler type of heat exchanger 78 where it is gasified and then passes in a gaseous state through the lines 80, 82 to the rocket type combustion chambers 36 where it combines with the heated hydrogen fuel. The second medium passing through the regenerative heat exchanger 78 is gaseous air which is tapped off from the main power 40 plant duct downstream of the compressor 22 and passes to the line 86 which leads around tubes 88 of the regenerative heat exchanger 78. The precooled air from around the tubes 88 then passes to the line 70 and the main heat exchanger 64 in the manner described above.

45 The mixture of hydrogen and gaseous air leading to the rocket type combustion chambers 36 is fuel rich so that an excess of hydrogen appears in the gases being emitted from the exhaust nozzle 42 immediately downstream of the turbine 38. The surplus of hydrogen then mixes with the air which is flowing from the compressor 22 via the annular chamber 90. The air and the gases emitted from the nozzle 42 are subsequently burned in the main combustion chamber 48 and then emitted 50 from the convergent-divergent nozzle 52.

55 As a result of this invention, it will be apparent that a high output power plant has been provided which is low in weight and has an extremely low specific fuel consumption. Furthermore, higher oxidizer to fuel ratios are obtained in the gas generator which results in a

60 temperature rise which makes for better combustion characteristics. Because of the higher turbine inlet temperatures less fuel is required to drive the turbine and in many cases it allows for operation at a reasonable afterburner temperature without having excess fuel in the afterburner combustion products. As a result, the thrust 65 specific fuel consumption will also be improved.

66 By using compressor bleed air rather than ram air for the liquefying source, the engine has better sea level static take-off capability. Also, the precooler is more effective than an expansion turbine because it cools the bleed air more effectively without excessive pressure

drops. The pressure drop is a very important consideration when designing the main heat exchanger and plays an important part in avoiding any possible cavitation problems in the liquid air pump.

Although only one embodiment of this invention has been illustrated and described herein, it will be apparent that various changes and modifications may be made in the construction and arrangement of the various parts without departing from the scope of this novel concept.

What it is desired to claim by Letters Patent is:

1. In a turbine type power plant including an air intake, an axial flow compressor receiving air from said air intake, a main combustion chamber receiving air from said compressor, a source of hydrogen fuel in a liquid state, an air-to-air regenerative heat exchanger, an air-to-fuel main heat exchanger in series flow connection with said regenerative heat exchanger, means for conducting a part of the air from the discharge end of said compressor to said regenerative heat exchanger to precool said air, means for conducting said precooled air immediately to said main heat exchanger to liquefy said air and to heat said fuel, means for conducting said liquid air to said regenerative heat exchanger to precool the gaseous air from said compressor and gasify said liquid air, a primary combustion chamber having a primary exhaust nozzle upstream of said main combustion chamber, means for conducting gaseous air from said regenerative heat exchanger and an excess of fuel from said main heat exchanger to said primary combustion chamber, a turbine receiving the gases produced by said primary combustion chamber for driving said compressor, and means for mixing the exhaust gases from said turbine and the air from said compressor for burning in said main combustion chamber including means for injecting fuel from said source into said main combustion chamber.

2. In a turbine type power plant including an air intake, said power plant comprising an outer casing and a central body forming inner and outer walls which define an annular duct, means downstream of said inlet for bleeding boundary air from along at least one of said walls and discharging said flow overboard of the power plant, a compressor in said duct receiving air from said inlet, a main combustion chamber adjacent the downstream end of said central body, a main exhaust nozzle downstream of said combustion chamber and downstream of the downstream end of said inner body, means for varying the area of said main exhaust nozzle, a source of hydrogen fuel in a liquid state, a regenerative heat exchanger, a main heat exchanger, means for conducting fuel from said source through one of said heat exchangers, a source of air, means for conducting air from said source through both of said heat exchangers in series whereby one exchanger is in an air-to-air heat exchange relation and the other exchanger is in a fuel-to-air heat

- 5 exchange relation, a rocket combustion chamber receiving an excess of fuel from one of said heat exchangers and air from the other heat exchanger, a turbine receiving gases only from said rocket combustion chamber and driving said compressor, a second exhaust nozzle downstream of said turbine and upstream of said main combustion chamber and exhausting gases into said main combustion chamber for mixing with the air from said compressor, and means for conducting fuel from said 10 source to said main combustion chamber including a heat exchanger adjacent said main combustion chamber.
- 15 3. In a turbine type power plant including an air intake, said power plant comprising an outer casing and a central body forming outer and inner walls, respectively, 15 which define an annular duct, means downstream of said inlet for bleeding boundary air from along said inner wall and discharging said flow overboard of the power plant, a compressor in said duct receiving air from said inlet, a main combustion chamber adjacent the downstream end of said central body and forming a continuation of said annular duct, a main exhaust nozzle downstream of said combustion chamber, means for varying the area of said main exhaust nozzle, a source of hydrogen fuel in a liquid state, a regenerative liquid air 20 to gaseous air heat exchanger, a main liquid fuel-to-air heat exchanger, means for conducting fuel from said source through said main heat exchanger, a source of air comprising a duct receiving air from the discharge end of said compressor, means for conducting air from said source through said regenerative heat exchanger then through said main heat exchanger and then back through said regenerative heat exchanger in succession, a rocket combustion chamber upstream of said main combustion chamber and carried by said central body, said rocket combustion chamber receiving an excessive amount of fuel from said main heat exchanger and air from said regenerative heat exchanger, a turbine receiving gases only from said rocket combustion chamber and driving said compressor, a second exhaust nozzle at the downstream end of said central body and upstream of said main combustion chamber and exhausting gases into said main combustion chamber for mixing with the air from said compressor, and means for varying the area of said second exhaust nozzle.
